(57) **CLAIM**

The ornamental design for a tube container, as shown and described.

DESCRIPTION

FIG. 1 is a perspective view of the tube container showing my new design;

FIG. 2 is a first side view thereof;

FIG. 3 is a second side view thereof;

FIG. 4 is a top view thereof; and,

FIG. 5 is a bottom view thereof.

The broken line showing of portions of the tube container is included for the purpose of illustrating environmental structure and forms no part of the claimed design.
